UNITED STATES PATENT OFFICE

ERNEST R. HENTSCHEL, OF WASHINGTON, DISTRICT OF COLUMBIA; JOHN OLSON, ADMINISTRATOR OF SAID ERNEST R. HENTSCHEL, DECEASED, ASSIGNEE TO WIRED RADIO, INC., OF NEW YORK, N. Y., A CORPORATION OF DELAWARE

MEANS FOR CONTROLLING THE AMPLITUDE OF ALTERNATING CURRENT

Application filed November 7, 1929. Serial No. 405,438.

My invention relates broadly to radio receiving systems and more particularly to a circuit arrangement for automatically controlling the amplitude of alternating currents in a radio receiving system.

One of the objects of my invention is to provide a radio receiving system having means for controlling the volume of the reproduced signaling energy in accordance with the amplitude of the signaling energy at the receiver.

Another object of my invention is to provide a circuit arrangement for a radio receiving apparatus having means controlled by the amplitude of the alternating current in the sound reproducing system for regulating the amplitude of the energy which is impressed upon the receiving circuit in accordance with the strength of the incoming signaling energy.

A further object of my invention is to provide a thermostatic system controlled by the amplitude of the alternating current in the sound reproducing system of a radio receiving circuit for regulating the amplitude of the signaling energy which may be impressed upon the signal receiving circuit and thus controlling the volume of the reproduced sound.

Other and further objects of my invention reside in the method of volume control in a radio broadcast receiver as set forth more particularly in the specification hereinafter following by reference to the accompanying drawings, in which:

Figure 1 schematically and diagrammatically illustrates the principle of my invention; Fig. 2 shows a modified arrangement of the regulating means employed for effecting volume control in the receiving system of my invention; and Fig. 3 shows my invention applied to a radio broadcast receiver for controlling the volume of reproduced system in accordance with the amplitude of the incoming signaling energy.

In radio broadcast receivers the tuning of the receiver from one frequency setting to another is accompanied by considerable noise and undesired interference, as the broadcasting stations operating on different channels

are quickly tuned in and out as the receiver is tuned through a particular band of frequencies. When distant stations are to be received, the receiver is maintained in its most sensitive condition and considerable annoyances experienced when the tuning control is operated through frequency settings which will permit response to local stations at severe volume. The result produced is not entertaining but extremely annoying as movement of the tuning control brings in fragments of a series of different programs which is often a source of distraction because of the loudness of the reproduced sound when the receiver is maintained in its sensitive condition.

By my invention I provide means for automatically controlling the amplitude of the signaling energy in the sound reproducing system. That is, under conditions of strong signals, the amount of energy supplied to the receiving circuit from the radio frequency energy collecting circuit will be reduced to a predetermined value for the operation of the sound reproducer system at that amplitude which will insure reproduction of sound at the proper volume. In the case of relatively weak sounding production on distant stations, the circuit of my invention automatically operates to place the receiver in its most sensitive condition for the reproduction of sound at the maximum value which is obtainable. When the receiver is tuned from one frequency setting to another, the extreme sensitivity of the receiver for weak signals is not detrimental in that the condition of the receiver is automatically changed when signaling energy of greater strength is received, so that reproduction of sound for local stations may be at the same volume as that of extremely distant stations.

The volume control of my invention is entirely automatic and does not depend upon the skill of the operator in adjusting cathode heating potential for the form of control as the receiver is tuned.

Referring to the drawings in more detail, reference character 1 designates an antenna system which includes primary winding 2 of high frequency transformer 3 and ground

connection 4 through the variable coupling condenser 5. The transformer 3 has secondary winding 6 which connects through the signal receiving circuit. In the diagrammatic showing in Figs. 1 and 2, I have illustrated by broken line 7 the connections to the signal receiving circuit which ultimately terminate in a final stage of power amplification which I have designated by electron tube 8. The electron tube 8 includes cathode 9 heated by any suitable means such as battery 13, control electrode 10 and plate 11. The output circuit which extends between plate 11 and cathode 9 includes the sound reproducing device 12, the source of plate potential 14, and the primary winding 15 of audio frequency transformer 16. The secondary winding 17 of audio frequency transformer 16 connects to a thermostatic wire member 18 which is supported at opposite ends at 19 and 20. The support at the end 20 is fixed in position but the end 19 is connected to the angularly movable shaft 21 of the coupling condenser 5 by means of a flexible cord 22 which may be wound around shaft 21 and securely affixed thereto. A cord 23 is wound around the shaft 21 in an opposite direction to the direction of winding of cord 22 and is affixed to the shaft 21. The opposite end of cord 23 is connected through spring 24 with the fixed support 25. The shaft 21 is journaled in suitable bearings which subject the angular movement of the shaft to minimum friction and is suitably counterbalanced as indicated at 45. The capacity elements or plates 26 which are carried by angular movable shaft 21 are light in weight and are counterbalanced by the weight 45 to allow movement of the shaft under conditions of displacement of the cord 22 which is wound around shaft 21. The fixed plates of the variable coupling condenser 5 have been designated diagrammatically by the single plate shown at 27 and connected to the antenna or radio frequency energy collecting circuit. The movable plates 26 and shaft 21 are connected to ground at 4.

The wire 18 is selected of such size and material that the characteristics of expansion and contraction may be utilized to control the angular displacement of shaft 21. When the amplitude of the alternating current in the sound reproducing system 12 is large, the wire 18 becomes warm and elongates. Cord 22 thereupon moves to the left and by reason of the spring tension 24 under which the angularly movable shaft 21 is maintained, the cord 22 wraps upon shaft 21, while cord 23 unwinds from shaft 21, resulting in the counter-clockwise movement of the plates 26 and the decreasing of the exposure between the set of stator plates represented at 27 and the set of rotor plates represented at 26.

65 In the modified form of circuit arrange-

ment illustrated in Fig. 2, the expansive wire element 18 is firmly anchored not only at the end 20 but also at its opposite end 28. A cord 29 is taken from the center of the heater element 18 and is wrapped around the angularly movable shaft as shown at 30 in a direction opposite to the direction of winding of the vertically extending cord 31 which is wrapped around the shaft as designated at 32. Cord 31 is maintained under tension by means of spring 33 which is fixed at its upper end as shown at 34. Under the condition of maximum signaling as represented in Fig. 2 of the drawings, wire 18 has expanded to maximum position and the coupling of variable condenser 5 is at a minimum. That is to say, the rotor plates 26 have moved to a position where there is minimum exposure with respect to stator plates 27. The position of the rotor plates with respect to the stator plates is selected with respect to the expansion and contraction of the wire element 18 to secure a maximum change in capacity in the series circuit to the antenna to control the volume of energy in the output circuit to the sound reproducer. In the arrangement shown in Fig. 2, the spring 33 takes up the slack which exists in heater element 18 as signaling energy of large amplitude occurs in the output circuit. It will be noted that the connections to the terminals 18a and 18b of the heater element 18 are sufficiently flexible to allow expansion or contraction of the heater element 18 and operation of the angularly movable shaft 21.

In Fig. 3, the compensating system is shown disposed directly in series with the antenna 1 and above the connection to the primary 2 of transformer 3. The expansion member 18 which connects through cord 22 to shaft 21 connects to the secondary winding 17 and transformer 16 whose primary winding 15 is disposed in series with the loud speaker 12 in the output circuit of the final stage of power amplification designated at 35. The radio broadcast receiver shown in Fig. 3 includes electron tubes 36, 37, and 38 connected in a tuned radio frequency cascade amplifier system in circuit with electron tube detector 39 and the audio frequency amplifier system constituting the electron tube 40 and the power amplifier electron tube circuit which connects to electron tube 35. The power supply for the cathodes of the electron tubes is obtained from any suitable source such as A battery 41. The negative bias potential for the amplifier tubes is obtained from C battery designated at 42, and the plate potential for the several tubes is obtainable from B battery system 43.

When the wire element 18 is cooled, the antenna coupling is maintained at maximum to produce maximum volume in reproduced sound in the output system. As the amplitude of the alternating current in the output circuit tends to increase, the wire element 18

elongates and under spring tension the condenser system 5 operates to reduce the coupling between the antenna circuit and the receiver, and thus decrease the amplitude of the current which is supplied through the receiving circuits to the loud speaker system to automatically regulate the amplitude of the current in the speaker circuit.

I have illustrated the shaft structure 21 diagrammatically, but it will be understood that this shaft is mounted in bearings having minimum friction and by properly proportioning the diameter or shape of the shaft at the point where the control cord wraps around the condenser shaft by means of a cam or other device, the angular displacement of the shaft 21 through various stages of elongation of the wire element 18 may be controlled through a given angular distance for the proper compensation of the receiving circuit for effecting control in volume.

While I have shown the circuit of my invention as applied to a radio receiving circuit, I desire that it be understood that my invention 25 may also be applied to the control of audio frequency currents used in modulating broadcast transmitters and in other speech frequency circuits where automatic control is desired.

30 The position of the rotatable shaft with respect to the expandable and contractible element may be predetermined and suitably calibrated for properly adjusting the operation of the compensating system by the desired 35 limits. In lieu of a variable condenser, I may employ other forms of variable impedance elements and provide various types of mechanical connections between the thermo-electric element and the movable element of 40 the variable impedance device in the signal receiving circuit.

It is understood that condenser 5 must not act too rapidly or else the volume will tend to follow minor variations in loudness of speech 45 or music. An appreciable time period is required for currents to produce changes in temperature in wire 18, and this, in part at least, automatically prevents operation of the control upon mere modulation alone. If the 50 ordinary time delay is not sufficient, any of the customary damping methods, which do not increase friction, may be applied to condenser 5. Two methods of arranging the condenser may be employed: (1) Immersion 55 in oil, and (2) the application of magnetic damping on a movable plate member, which may be either one of those used as part of the variable capacity, or an additional plate secured to the rotor, adjacent one end of the 60 shaft.

The control system of my invention will also operate in the radio frequency circuit of a receiver if sufficient amplification is employed. Winding 17 may couple to one of the 65 radio frequency transformers, or a special

radio frequency transformer may be placed in one of the circuits. For example, such a transformer may be placed in the plate lead of tube 38, either above or below the usual coupling transformer.

70

While I have described preferred embodiments of my invention, I desire that it be understood that modifications may be made and that no limitations upon my invention are intended other than are imposed by the 75 scope of the appended claims.

What I claim as new and desire to secure by Letters Patent of the United States is as follows:

1. In a system for automatically controlling the amplitude of alternating current, an output circuit, an input circuit, temperature actuated responsive means in said output circuit controlled by amplitude changes in current delivered to said output circuit from said input circuit, and means in said input circuit for controlling the amplitude of current delivered to said input circuit, said last mentioned means being controllable in accordance with the operation of said first mentioned means.

2. In a system for automatically controlling the amplitude of alternating current, an output circuit, an input circuit, a circuit for impressing variable alternating current 95 upon said input circuit, thermo-electric means responsive to changes in amplitude of current in said output circuit according to corresponding changes of the current existent in said input circuit, and means connected to 100 said input circuit for regulating the current supplied thereto, said last mentioned means being directly controllable by said thermo-electric means for regulating the amplitude of current in said output circuit.

3. In a system for automatically controlling the amplitude of alternating current, an input circuit, an output circuit, means for supplying high frequency energy to said input circuit for controlling the operation of 110 said output circuit, means connected with said input circuit for regulating the amplitude of high frequency current supplied thereto, and thermo-electric means connected with said output circuit and responsive to changes in 115 amplitude of the current therein for controlling the operation of said second mentioned means for correspondingly changing the amplitude of the effective current in said output circuit which is delivered from said input circuit.

4. A volume control system for electron tube amplifiers in combination with a cascade amplifier circuit having an input system and an output system, a sound reproducer connected to said output system, a thermo-electric device connected with said output system, a signal receiving circuit connected with said input system, and means in said signal receiving circuit directly controlled by said 125 130

thermo-electric device in said output circuit for regulating the amplitude of current supplied to said sound reproducer in said output system.

5. A volume control for an electron tube amplifier having an input system and an output system, a sound reproducer connected with said output system, a signal receiving circuit connected with said input system, means in said signal receiving circuit for regulating the amplitude of current delivered to said input system from said signal receiving circuit, and a temperature actuated member controlled by the amplitude of current in said output system for correspondingly adjusting said means in said signal receiving circuit for regulating the amplitude of current which passes through said sound reproducer in proportion to the amplitude of signaling energy in said signal receiving circuit.

6. A volume control circuit for signal receiving systems comprising in combination with an electron tube amplifier, an input system, an output system, a sound reproducer connected in said output system, a thermo-electric device energized from said output system, a signal receiving circuit connected to said input system, means in said signal receiving circuit for adjusting the amplitude of current delivered to said input system, and means interconnecting said thermo-electric means and said means in said signal receiving circuit for automatically adjusting the amplitude of current through said sound reproducer according to the amplitude of energy existent in said signal receiving circuit.

7. In a volume control system for an electron tube amplifier, a signal receiving circuit, an input circuit connected thereto, an amplification system, an output circuit connected to said amplification system, a sound reproducer connected with said output circuit, a thermo-electric element connected to said output circuit, means in said signal receiving circuit for regulating the amplitude of received current supplied to said input system, and a connection between said thermo-electric element and said means for controlling the amplitude of current supplied to said sound reproducer in accordance with the amplitude of current in said signal receiving circuit.

8. A volume control for amplifier systems including an input circuit, an output circuit, a sound reproducer connected with said output circuit, means connected in said output circuit and expansible or contractible according to the amplitude of current in said output circuit, a signal receiving circuit connected with said input circuit, and means for varying the coupling between said signal receiving circuit and said input circuit, said last mentioned means being controllable in proportion to the expansion or contraction of the means in said output circuit for regulat-

ing the amplitude of current supplied to said input circuit for operating said sound reproducer in said output circuit.

9. A volume control for amplifier systems, including an input circuit, an output circuit, a sound reproducer connected with said output circuit, means connected in said output circuit and expansible or contractible according to the amplitude of current in said output circuit, a signal receiving circuit connected with said input circuit, a variable impedance for modifying the coupling between said signal receiving circuit and said input circuit, and a mechanical connection between said expansible or contractible means with said variable impedance for modifying the effect of the received signal current upon said input circuit and correspondingly controlling the operation of said sound reproducer and uniform amplitude independent of amplitude changes in the signaling current.

10. A volume control for amplifier systems including an input circuit, an output circuit, a sound reproducer connected with said output circuit, means in said output circuit and expansible or contractible according to the amplitude of current in said output circuit, a signal receiving circuit connected with said input circuit, and a variable condenser connected in said signal receiving circuit, the capacity of said condenser being variable in accordance with the expansion or contraction of said means in said output circuit for regulating the amplitude of current supplied to said input circuit and correspondingly controlling the operation of said sound reproducer at predetermined volume.
